SUPPORT FOR WIRE REELS

Ernest P. Moslo, Cleveland, Ohio

Application March 17, 1937, Serial No. 131,358

5 Claims. (Cl. 242—77)

This invention relates to reels for coils of wire and to improvements in the supporting structure therefor.

In wire drawing operations and in the manufacture of wire products, it is customary to work the stock from coils which are arranged in relation to the fabricating machine to accommodate the most effectuous feed thereto and the most expeditious renewal of stock to the coil supporting frame. To this end some effort has been directed, in the past, to the construction of a coil frame having a reel so mounted thereon that the coil could be tilted to a vertical position and slid upon the reel, which was then swung to a horizontal plane or the stock feeding position.

Devices of this character heretofore constructed were difficult of operation and necessitated the expenditure of considerable manual effort to swing the reel and coil to a horizontal position as no counter-balance was embodied therein which was effective throughout the operative loading cycle of the device. Moreover, the coils when mounted upon the reels heretofore in use were subject to vibratory reactions in the frame, were unstable and inadaptable of diversified usage or unusual application.

In the present invention a counter-balance is provided to alter the center of gravity of the reel and coil during the adjustment thereof and thus eliminate the arduous effort heretofore necessary to position the coil in its working position. The invention further embodies certain refinements in the reel and supporting structure therefor which facilitate the more rigid securing of the coil upon the reel and accommodate the device to more general application than is possible in similar devices in common use at the present time.

In addition to the foregoing objects and advantages, the invention comprehends a structure which is economic of manufacture, sturdy of construction, and a device adapted for ready manipulation.

In the drawings wherein the preferred embodiment of the wire coil supporting mechanism is illustrated:

Fig. 1 is a side elevational view of the supporting stand and reel illustrated as adjusted in its vertical position;

Fig. 2 is a similar side elevational view illustrating the reel in its horizontal position;

Fig. 3 is a vertical section through a reel supporting member, the section being indicated on the line 3—3 of Fig. 1, the drawing being shown upon an enlarged scale and having the reel re-

moved and fragmentary portion of the base broken away;

Fig. 4 is a transverse sectional view illustrating the reel latching mechanism, the section being taken on a plane being indicated by the line 4—4 of Fig. 3;

Fig. 5 is a plan view of the coil retention member;

Fig. 6 is a plan view of the base ring constituting a portion of the coil reel; and

Fig. 7 is a detailed view shown upon an enlarged scale of a fragmentary portion of the reel bearing and the reel brake associated therewith.

Fig. 8 is a view in perspective of a fragmentary portion of the reel ring, the spoke construction therefor and the arm supporting block and clamp.

Referring first to Fig. 1, the wire coil supporting structure comprises a base 10 of prismatical configuration, being preferably formed of welded sheet metal plates and having a hand hole and removable cover plate 11 therein so that the chamber formed thereby may be partially filled with a comminuted material 60 as indicated by the dotted line in Fig. 1 to provide the necessary weight for the base of the device. Upon the base 10 there is a pair of spaced vertical arms or stanchions 12 which are also formed of sheet metal plates welded to form a box section generally of triangular configuration. The upper portion of the stanchions 12 is bored to receive trunnion bearings 13 having pintles 14 therein extended inwardly to support a counterweight member 15. The counterweight member as shown is triangular in side elevation, being formed of sheet metal plates welded along their peripheral edges to constitute a box section for the reception of a comminuted material 61 such as shot, or small fragments of broken castings accessible through a hand hole and cover plate 15a. The upper portion of the counterbalance member 15 is formed with bearing blocks 16 welded to the inner face of the side walls of the housing and provided with journal bearings 17 for the reception of the inner ends of the pintles 14. The lower forward end 18 of the counterweight housing 15 is arcuate to facilitate the rotation of the housing upon the pivotal support provided by the pintles 14.

Within the upper portion of the counterweight housing 15 there is a post 19 welded in place and protruding inwardly into the housing 15, the end thereof being connected with a transverse tubular cross member 20. The outer free end of the post 19 is formed with a boss 21 for the reception of a setscrew 22 which retains the reel arbor 23. In addition to the setscrew 22 the reel arbor 23 is

55

restrained from inward movement within the post by a collar 24 welded or otherwise affixed within the post. Telescopically engaged within the arbor 23 there is a rod 25 having a knurled sleeve 26 on the outer end thereof pinned to the rod 25 and counter bored at its inner end for engagement upon the shouldered end portion of the arbor 23. The inner end of the rod 25 is provided with a pin 27 which, as shown in Fig. 4, is eccentrically mounted to form a cam or key blade disposed to extend inwardly through an opening in the tube 20 for engagement with the shoulders of a notch 28 machined in a throw bolt 29. The throw bolt is mounted for reciprocative movement within the tube 20 and is formed with a conical end portion 30 urged by a compression spring 31 to engage either of the conical bores 32 or 33 in a plate 34 welded upon the inner face of the contiguous arm or stanchion 12. The function of this assembly is to lock the housing 15 in reel supporting position either in the vertical or horizontal plane as illustrated respectively in Figs. 1 and 2, such structure affording the operator the opportunity of grasping the sleeve 26 to raise or lower the coil while he is in position in front of the reel. By rotating the shaft 25 the operator will cause the pin 27 to engage the shouldered portion of the slot 28, overcome the spring 31, and cause the retraction of the throw bolt 29, whereupon the reel may be rotated to the desired position, then by releasing the sleeve 26, the spring will force the throw bolt into locked engagement.

The wire coil reel comprises a ring 40 having spokes 41 preferably of I-beam section joined with the inner peripheral edge of the ring and connected to a hub member 42 bored for sliding engagement upon the arbor 23. Adjacent and parallel each of the spokes 41 in the ring 40 there is a secondary rail 43 secured to the inner peripheral edge of the ring and to the hub and face of the adjacent spoke 41. Such construction affords a bearing surface for the finger blocks 44 which comprise a rectangular body having a tongue or key 45 in the base portion thereof for engagement between the rails 43 and the spokes 41. The blocks are bored to receive bolts or studs 46 which extend through the opening between the spokes 41 and rails 43 and beyond the lower face thereon. The free ends of the bolts are provided with nuts 47 formed to engage the lower faces of the rails and spokes and as illustrated in Fig. 1 provided with a crossarm or pin to facilitate the ready adjustment thereof. The outer faces of the blocks 44 are provided with fingers 48 having the free ends thereof bent inwardly to readily accommodate the reception of the coil of wire when introduced thereover. The outer ring 49 (Fig. 5) is formed with a hub member 50 bored for reception upon the reel arbor 23, the radial spokes 51 therein being connected with the inner periphery of the ring 49. Adjacent one of the spokes 51 and, parallel thereto there is a rail 52 welded to the inner rim 65 of the ring and to the contiguous spoke 51. The rail is spaced from the spoke 51 a suitable distance to provide for the reentrant engagement of one of the fingers 48 between the rail and adjacent spoke and is provided to prevent rotative movement of the ring when positioned upon the coil. The ring or wheel member 49 although shown somewhat lighter in structure than the ring 40, may be of any suitable size to afford the necessary weight for the various types of wire 70 to be used upon the reel, as this member com-

prises merely a compression element to constrain undue freedom of the uppermost convolutions of wire in the coil as the wire is being fed therefrom to the fabricating machine. The hub 42 of the ring 40 is preferably formed with anti-friction bearings 53 to minimize the tension on the wire as it is fed to the machine. The reel may be longitudinally positioned upon the arbor 23 by a collar 54 which is secured in position thereon by a set screw 55. Upon one of the spokes 41 of the ring 40 there is an arm 56 preferably secured thereto by a bolt 57, the free end of the arm being bored to receive the shank of a brakeshoe 58 which is spring-urged upon the face of the arbor 23 to restrain the rotative movement 15 of the reel when the fabricating machine is suddenly stopped or exerts undue tension upon the wire.

In operation the attendant, when replacing a coil of wire, first lowers the reel to the vertical position shown in Fig. 2, then removes the ring 49. In the event a coil of wire, or heavier gauge or greater size and weight is to be used, the attendant will remove the counterweight housing cover plate 15a and add sufficient quantity 25 of shot or comminuted scrap iron to suitably balance the weight of the coil. The attendant then tips the coil of wire upon its edge, adjusts the fingers 48 so as to engage the inner periphery of the coil of wire and then tighten nuts 47 to 30 secure the blocks 44 in locked adjustment. The next operation in sequence is to rotate the rod 25, thus retracting the throw bolt 29 and then elevate the coil by rotating the counter-balance member 15 to the vertical position shown in Fig. 35 1. Due to the configuration of the chamber formed in the housing 15, the comminuted material or ballast 61 will shift towards the rear of the chamber so that the center of mass will remain rearward the vertical axis of rotation of 40 the housing, thus supporting the reel and wire coil in a state of equilibrium throughout the entire cycle of rotative adjustment of the housing. It will be readily recognized that with such construction less effort will be necessary to move the 45 reel to its adjusted position than is required with structures which are formed with a weighted pendulum of fixed length which will reach or approach a dead center within its arc of rotation.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

I claim:

1. A wire coil supporting structure comprising a hollow base member having an opening therein for the admission of a finely divided material to increase the weight of said base, a pair of vertical arms on said base member, a hollow counter-balance member intermediate said arms and pivotally supported thereon, an arbor on said counter-balance member, a wire reel pivotally mounted on said arbor, a throw bolt reciprocatively mounted in said counter-balance member and engageable in an opening in one of said arms for locking said counter-balance member in a vertical or horizontal position, and a finely divided material constituting a ballast medium in said counter-balance member for shifting the center 70 65 75 80 85 90 95 98 99 100

of gravity thereof during the rotative adjustment of the counter-balance member from its horizontal to vertical position.

5. A wire coil supporting structure comprising a base member, a pair of stanchions thereon, one of said stanchions having a pair of openings therein, a counter-balance member intermediate said stanchions and pivotally mounted thereon, a tubular arbor on said counter-balance member, a wire reel rotatably mounted on said arbor, a rod mounted for oscillating movement in said arbor, and extended beyond said reel, a cam in the inner end of said rod, a throw bolt in said counter-balance member engageable with said 10 openings in said stanchions to lock said counter-balance member in a vertical or horizontal position, said cam in said rod being engaged with said throw bolt and operatively controllable from a positive adjacent the outer face of said wire 15 reel.
15. A wire coil supporting structure comprising a sheet metal hollow base member, a ballast material therein, a pair of vertical arms thereon, a hollow counter-balance housing member intermediate said arms and pivotally supported thereon, an arbor on said housing member, a wire reel pivotally mounted on said arbor, means for locking said housing member in a vertical or horizontal position and ballast material within said 20 hollow counter-balance housing member for shifting the center of gravity during the adjustment thereof.
25. A wire coil supporting structure comprising a base member, a pair of stanchions thereon, a counter-balance member intermediate said stanchions and pivotally mounted thereon, an arbor mounted on said counter-balance member, a wire reel comprising 5 a ring of channel section, a hub member, pairs of parallel I beams constituting spokes connecting said ring to said hub member, blocks spanning each pair of said spokes, wire coil supporting fingers mounted thereon, bolts extended 10 through said blocks and between the parallel beams of said spokes, and nuts on said bolts engageable with the opposed face of said beams for clamping said blocks upon said spokes.
30. A wire coil supporting structure comprising a hollow sheet metal base member having an opening therein, a detachable cover therefor, a pair of vertical arms on said base member, a hollow sheet metal counter-balance member pivotally mounted between said arms, said counter-balance member having an opening thereon, a detachable cover therefor, an arbor mounted on said counter-balance member, a wire coil supporting reel rotatably mounted on said arbor, means controllable through said arbor for locking 25 said counter-balance member to said arms in a plurality of adjusted positions, a finely divided material constituting a ballast in said counter-balance member for shifting the center of gravity thereof during rotative adjustments, and a finely 30 divided material in said base member to increase the weight thereof.

4. A wire coil supporting structure comprising
